CARRIER FOR A GARMENT HANGER OR THE LIKE

Allie V. Peoples, Jr., 7103 Brentwood Ave.,
Oklahoma City, Okla.

Filed Dec. 16, 1966, Ser. No. 5,067

Term of patent 14 years

(Cl. D80—8)

FIGURE 1 is a side elevational view of a carrier for a garment hanger or the like, showing my new design;

The dominant features of my design reside in the portions shown in full lines, it being understood that the broken line representation of a garment hanger in FIGURE 4 is for purposes of illustration only.

I claim:

The ornamental design for a carrier for a garment hanger or the like, as shown and described.
